UNITED STATES PATENT OFFICE.

SIMON HOFFMANN, OF NEW YORK, N. Y., ASSIGNOR, BY MESNE ASSIGNMENTS, TO LOCOMOTIVE SUPERHEATER COMPANY, OF WILMINGTON, DELAWARE, A CORPORATION OF DELAWARE.

BOILER WITH FIRE-TUBE SUPERHEATER.

1,104,756.

Specification of Letters Patent. Patented July 21, 1914.

Application filed January 12, 1912. Serial No. 670,734.

To all whom it may concern:

Be it known that I, SIMON HOFFMANN, a subject of the Emperor of Austria-Hungary, and a resident of New York, county 5 and State of New York, have invented a new and useful Improvement in Boilers with Fire-Tube Superheaters, of which the following is a specification.

My invention relates to superheaters for 10 steam boilers of the fire tube type, and has for its object to simplify and cheapen the construction of the superheater, to reduce the space required in the smoke box for the application of the superheater, and to make 15 the means by which the superheater tubes are connected respectively with the steam supply of the boiler and with the engine cylinders simpler, cheaper, and easier to maintain.

20 More particularly my invention relates to the construction of the headers, as they are called, or collecting chambers usually interposed in the path of the steam at the two ends of the system of superheater tubes.

25 In superheaters of the type referred to the general practice has been to place in the smoke box a header casting, having one chamber connected with the wet steam supply and with one end of the superheater 30 tubes, and a second chamber connected with the other end of the superheater tubes and with the engine cylinders, the first chamber serving to distribute wet steam to the superheater tubes, and the second 35 chamber serving to collect the superheated steam and distribute the same to the cylinders. There are, in some constructions, two distinct castings, one being used for each header chamber, while in other constructions a single casting, having two 40 chambers as above, has been employed. The use of these headers by reason of their necessary very considerable weight and size, as also by reason of the complicated coring required in their manufacture, as well as by 45 reason of the considerable machining which has been necessary, has made them expensive both as to cost of manufacture and as to cost of installation.

50 In my invention described herein, I have avoided the above stated disadvantages by substituting for these hitherto used cast headers, a header which forms an integral

part of the boiler. To accomplish this I use preferably a portion of the front tube sheet of the boiler and a portion of the boiler sheet as header walls, or I may use a portion of the front tube sheet without using any portion of the boiler shell.

My invention will be better understood 55 by referring to the drawings accompanying, which are hereby made a part of this specification, in which several modifications of my invention are shown as applied to a locomotive boiler of the fire tube type.

60 In the drawings Figure 1 represents an elevation of a preferred form of my invention, the right hand half being taken from in front of the tube sheet and the left hand half being taken approximately along the 65 line 1—1 of Fig. 2; Fig. 2 is a section taken along the line 2—2 of Fig. 1; Fig. 3 is an elevation similar to that of Fig. 1 showing a modified form of my invention; Fig. 4 is a section taken along the line 4—4 of 70 Fig. 3; Fig. 5 is an elevation similar to that of Fig. 1 showing another modification of my invention, the lower half of the boiler being broken away; Fig. 6 is a section taken along line 6—6 of Fig. 5; Fig. 7 is an 75 elevation similar to that of Fig. 5 showing still another modification of my invention; Fig. 8 is a section along the line 8—8 of Fig. 7; Fig. 9 represents an elevation 80 similar to that of Fig. 1, showing a fifth 85 modification of my invention; and Fig. 10 is a section taken along the line 10—10 of Fig. 9.

Corresponding letters denote corresponding parts throughout the drawings except 90 where otherwise specifically stated.

In the drawings Figs. 1 and 2, the front tube sheet *a* is provided with the usual peripheral flange *b* for engagement with and riveting to the boiler shell *c*. The upper part of this tube sheet is off-set forwardly a suitable distance so as to have a horizontal portion *d* extending across the boiler and a front portion *e*; a circular segment *f* of boiler iron riveted to the boiler 95 shell and riveted or welded to the main or lower segment *f'* of the tube sheet makes up, with the boiler shell and the portions *d* and *e*, four walls of a chamber which is again divided into two chambers or head- 100 ers by a partition wall *g* spaced above the 105

portion d . The upper header h is the saturated or wet steam header having an opening i for attachment to a steam supply pipe (not shown) leading from the steam dome of the boiler, while the lower header j is the superheated steam header having two openings k k' for attachment to steam pipes (not shown) leading to the engine cylinders. The superheater elements l are arranged in the fire tubes m in the usual manner and have their ends bent upwardly toward the header wall d . The superheated steam ends n of each element, open directly through this wall into the lower header j while the saturated steam ends o open into steam thimbles p which pass through the header j so as to open into the upper header h . As indicated in the drawings the ends n and o of a single element are arranged side by side and fixed in position by a clamp q and a single nut bolt system r but this, while a preferred mode of connection, is not an essential one in the practice of my present invention. Similarly the particular arrangement of the fire tubes and superheater elements with reference to one another and of the superheater elements with reference to the fire tubes is not essential, though preferred, and any desired arrangement of fire tubes and superheater elements whether taken alone or with reference to one another may be employed within the spirit of my invention. The particular method of connecting the ends of the superheater elements to the headers is also not essential to my invention. Stays s of conventional type may be suitably placed to strengthen the construction. Pet-cocks t at the lowest point of the saturated steam header on each side of the boiler serve to drain off any water of condensation which may collect.

In the modification set forth in Figs. 3 and 4, the front tube sheet a , instead of being offset forwardly in its upper part, is given its usual flat form, and the two header chambers h and j are constituted by circular segments u' and u^2 of boiler iron spaced respectively forwardly and to the rear of the upper part of the tube sheet and provided with flanged portions above and below for attachment to the boiler shell and to the tube sheet; as shown the upper flange of segment u' engages the inner surface of the tube sheet flange. Openings i' and k' are provided as before for the saturated steam connection and for the superheater steam connections respectively. The ends n' and o' of the superheater elements are bent backwardly in the arrangement shown, so as to enter the headers from the front instead of from below as in Figs. 1 and 2 but this is a mere matter of convenience dependent principally upon the dimensions chosen for the segment u' , and its flanges.

The construction shown in Figs. 5 and 6 is much the same as that of Figs. 1 and 2 except that the segment constituting the partition wall g and the portion d of the tube sheet of the latter figures are exchanged so that a portion g' of the tube sheet itself separates the two chambers h and j . 70

Figs. 7 and 8 show a construction in which no part of the boiler shell is used as a header wall. The superheated steam header j is formed exactly as in Figs. 3 and 4, the tube sheet separating the two headers, but the segment u^3 (corresponding to u^2 of Fig. 4) is flanged toward the tube sheet at some distance below the boiler shell. A pipe v inside the boiler leads from the outer opening i^2 (the latter to be joined to the steam dome of the boiler) to an opening i^3 into the superheated steam header h . The ends n' , o' of the superheater elements are bent backwardly as in Figs. 3 and 4. 75 80 85

Figs. 9 and 10 show a modified form of my invention in which the two headers h and j comprise similar flanges or flattened rings w and w' extending across the upper outer face of the front tube sheet a , said rings being separated by a plate x constituting a wall common to the two headers. A second plate x' constitutes the remaining wall of the outer header w' and the front 90 95 tube sheet a the remaining wall of the inner header h . The rings w , w' and plates x , x' are preferably welded together and to the tube sheet. Openings i and k for saturated and superheated steam are provided as 100 before.

In all of the various constructions shown the tube sheet with the segments necessary to constitute the header walls may, preferably, be built up outside and put into the 105 boiler as a completed whole leaving nothing to be done except the placing of the various stays and the riveting to the boiler shell.

I claim—

1. In a steam boiler provided with fire tubes, a superheater comprising a pair of headers one of which employs a part of the front tube sheet as part of its wall, superheater elements held within some of the fire tubes each of said elements having a pair of ends one of which connects with a header while the other passes through said header into the remaining headers, and steam connections between the headers and the steam supply and engine cylinders respectively. 110 115 120

2. In a steam boiler provided with fire tubes, a superheater comprising a pair of headers part of the front tube sheet being employed as a wall common to the two headers, superheater elements held within some of the fire tubes and having their ends connected with the two headers, and steam connections between the headers and the steam supply and engine cylinders respectively. 125

3. In a steam boiler provided with fire 130 135

- tubes, a superheater comprising a pair of headers one on each side of the front tube sheet, part of which tube sheet constitutes a partition wall common to both headers, 5 superheater elements held within some of the fire tubes and having their ends connected with the two headers, and steam connections between the headers and the steam supply and engine cylinders respectively.
- 10 4. In a steam boiler provided with fire tubes, a superheater comprising a pair of headers one on each side of the front tube sheet part of which tube sheet constitutes a partition wall common to both headers, 15 superheater elements held within some of the fire tubes each of said elements having a pair of ends one of which connects with a header while the other has connecting means passing through said header into the remaining header, and steam connections be- 20
- tween the headers and the steam supply and engine cylinders respectively.
5. In a steam boiler provided with fire tubes, in combination with the front tube sheet, segments joined to said tube sheet so as to constitute, with a portion of the same, 25 wall surfaces of two header chambers, superheater elements held within some of the fire tubes and having their ends connected with the two headers, and steam connections between the headers and the steam supply and engine cylinders respectively. 30
- In testimony whereof I have hereunto set my hand in the presence of two subscribing witnesses.

SIMON HOFFMANN.
